MAGNETIC TAPE REEL RACK WITH ADJUSTABLE DIVIDERS

Bo Allan Dagarp, Hagerstensvagen 280,
S-126 54 Hagersten, Sweden

Filed June 25, 1973, Ser. No. 373,599

Term of patent 14 years

Int. Cl. D6—04

U.S. Cl. D6—185

The figure is a perspective view of a magnetic tape reel rack with adjustable dividers showing my design.

I claim:

The ornamental design for a magnetic tape reel rack with adjustable dividers, substantially as shown.
